UNITED STATES PATENT OFFICE

OTTO H. KIESELER, OF CLEVELAND, OHIO, ASSIGNOR TO THE CHAMPION SPRING COMPANY, OF CLEVELAND, OHIO, A CORPORATION OF OHIO

BACK-REST FOR BEDS

Application filed November 5, 1928. Serial No. 317,347.

This invention relates to back rests for beds, and relates to pivoted back rests attached to the frame of beds, cots or couches, such attachment being adapted to adjustment 5 at various angles above the bed rails, and also adapted to foldable relation therewith, even to total collapse against the main bed frame for purpose of convenient storage or when the occupant of the bed desires a horizontal 10 position therein.

It is an object of my invention to provide a back rest attachment for bed frames that shall be very readily adjusted as to inclination with the frame, and which shall also require very little power applied thereto to 15 collapse the same. Adjustable back rests are known, but when the upper inclination of the device has been reached, difficulty has heretofore been experienced in disconnecting the 20 adjusting elements holding the attachment in the upper position. This difficulty I have overcome by my novel adjusting means.

It is a special object of my invention in addition to providing adjusting means for holding the back rest attachment in proper inclination with the frame to provide such connection of a nature which may be disconnected for foldable relation with the frame, without requiring direct manipulation of the 25 supporting braces, a slight upward lifting of the rest being the only actuating movement essential for lowering the back rest to the extreme lower position. This I regard as an exceedingly valuable asset and one which I 30 believe to be wholly novel.

With these and other objects in view which will be explained hereinafter, my invention consists in the described structure set forth in the appended claims and illustrated in the 35 accompanying drawing, in which—

Figure 1 is a perspective view of the head portion of a cot frame embodying my invention;

Figure 2 is a structural detail shown in a central longitudinal vertical section of the parts shown in Fig. 1, but indicating the back rest positioned one notch lower than in said view;

Figure 3 is a similar view, but showing the parts almost collapsed; and

Figure 4 is a transverse section taken in the plane indicated by the line 4—4 of Fig. 2. The cot frame upon which I have illustrated my novel back rest attachment, is formed of conventional angle bars 10 which 55 may be used to provide side members 11 and suitable cross members 12 at either end. It is immaterial so far as the operation of my attachment is concerned, how the end members are secured to the side bar, or how leg 60 members are attached at the corners of the frame. I have shown leg members 13 connected to the side bars by braces 14.

My improved back rest comprises parallel side bars 15 usually of angle iron connected by cross bars 16 having bent ends usually riveted to the side bars. The upper ends of the bars 15 are usually connected by a cross bar while the lower ends 17 may remain disconnected. The inner surfaces of the ends 17 have connected thereto at right angles, short bars 18 by means of rivets, and the lower ends of the bars 18 are provided with outwardly extending rivets 19 adapted to travel along beneath and lengthwise of the side bars 70 10. The latter structure being intended to provide an adjustable position of the ends 17. Further provision for this function results from locating the vertical flange 20 of the angle bars 10 on the outer side, and the horizontal flange at the lower side, so that the ends 17 may travel upon the said horizontal flange and within the flanges 20.

The back rest attachment is pivoted to the cot frame by providing downwardly extending bars 21 fixedly secured to the under surface of the horizontal flange of the cross bar 12 adjacent its ends; and then connecting the lower ends of bars 21 to the side bars 15 of the back rest by elongated parallel braces 22 whose upper ends are pivoted to the bars 15 intermediate their ends. The back rest is then pivoted to the cot frame at varying inclination thereto and at a fixed distance from the bars 21. The back rest is further provided with a swinging bail having a cross bar 23 and side bars 24 which is pivoted to the side bars 15 at points 25 somewhat nearer the upper ends of the bars 15 than are the braces 22. The back rest then is supported 85 90 95 100

positively upon the braces 22 and the bars 10, and also adjustably supported upon the bail 23 in the manner about to be described.

A ratchet bar 26 is mounted in spaced relation upon each of the braces 22 in the same plane therewith, and slightly spaced from the pivots 27 for attachment with the bars 21. The said bars 26 are vertically spaced from their respective support braces 10 by a plurality of U-shaped plates 28 whose ends are fixedly secured to the adjacent edges of the support braces and ratchet bars on the outer surfaces of each, so that an unobstructed passage between the parts is afforded for an appreciable distance extending outward through the slot 29, as clearly shown in all the views of the drawing.

These spaced bars 26 are mounted above the support braces 22, and are provided with ratchet teeth 30 upon their upper edge 31, which teeth are directed toward the rest bars 15. Such spacing of the parts 22 and 26 in the same vertical plane affords an open slot 29, except the lower entrance nearest the bar 21 where the slot is obstructed by a swinging gate 32 pivoted at 33 to the lower end of the bar 26 and swinging in the same plane as the said bar, thereby opening the slot 29 by a force operating downward along the slot 30 against the gate 32, but resisting entrance to said slot from below, by reason of the provision of a pin 34 on the outer surface of the brace 22 almost directly beneath the pivot 33 on the bar 26. A slender body may therefore travel downward through the inclined slot 29 opening the gate 32 and permitting the latter to again close the opening, but resisting entrance of the same body into the slot 29 from the lower opening, because of the pin 34 positively preventing swinging of the gate member in an upward direction. The function of this relation of parts will be explained below.

The side bars 24 of the bail are provided with outwardly-extending pins 35 which by gravity bear against the teeth 30 as the rest is raised in adjustment, and travelling downward through the slot 29 and leaving the same at the lower portion by striking the gate 32 and opening the same, and again rising up along the ratchet teeth 30 on its return movement.

In operation, the back rest comprising the bars 15 and 16 is supported in its inclined position upon the pivots 25 forming the connection with the bail 23, and upon the pivots connecting the braces 22 with the bars 15, the lower ends 17 of the back rest are supported upon the horizontal flanges of the bars 10, and slide therealong as the rest is adjusted. The pins 19 beneath the bars 10 hold the rest in contact with the frame bars. The support braces 22 provide the central hinge elements, while the bail 23 holds the rest in the adjusted inclination intended.

The movement of the bail pins 35 about the ratchet bars 26 determines the particular position of the rest upon the cot frame. When the rest is lowered to its limit, it is intended that the bars 15 of the attachment shall lie upon the horizontal flanges of the bars 10 of the cot frame, while the pins 35 then rest upon the lower ends of the braces 22, as indicated in dotted lines in Fig. 3 of the drawing.

When the upper end of the rest is raised, the pins 35 ride from their lowermost position shown in dotted lines in Fig. 3, upward along the edge of the closed gate 32, as shown in dotted lines in said figure along the edges 31 until they fall into one of the notches 30 when the rest is released. Such position is shown in Fig. 2. When the upper end of the rest is further raised after the pins 35 have left the last notch 30, the pin 35 will then drop by gravity down upon the edge of the brace 22, which is the movement indicated in dotted lines in Fig. 2. If the rest is now permitted to fall, the pins 35 will travel down the full length of the slots 29 until they will encounter the swinging gates 32 which will open to permit the pins to pass by them, which is the movement indicated in full lines in Fig. 3. The upper end of each gate 32 is provided with an extended tip 36 which may strike the plate 28.

The ratchet bar 26 may have any desired length, depending upon the length of the back rest and length of the bars 24. The number of notches 30 in the bar 26 may also be widely varied in number to determine the desired variance in the inclination of the back rest. It is of course, wholly immaterial what the character of the supporting legs 13 is, or what the nature of their attachment to the bed frame is. In fact, the particular operation of the back rest is not at all dependent upon the arrangement of the supporting legs or whether the bed frame has legs of any kind.

It is to be understood that various other changes in construction may be made as may prove expedient, and fall within the scope of the appended claims.

Having described my invention, what I claim and desire to secure by Letters Patent, is:—

1. A back rest attachment for a cot frame, having supporting braces pivoted thereto and to said frame, the lower ends of the back rest being adapted to ride slidably upon and lengthwise of said frame, adjusting mechanism including ratchet bars fixedly secured in vertically spaced relation from said braces by the provision of U-shaped members whose ends are secured to the ratchet bar and the supporting brace positioning said members in alinement with the said space between brace and bar, and said ratchet bars having a series of ratchet notches therein, and an

adjusting bail swinging from said attachment and carrying outwardly projecting pins on its side members adapted to enter any one of said notches to hold the back rest in adjusted position, the supporting braces being pivoted to said attachment between the said adjusting bail and the lower ends of the attachment.

2. A back rest attachment for a cot frame, comprising side bars adapted to ride upon the side rails of said frame and carrying on their lower ends, outwardly extending pins sliding beneath said rails, brace bars pivoted to said side bars and side rails and carrying 10 ratchet bars secured thereto and spaced thereabove in a common vertical plane by the provision of a plurality of offset U-shaped members secured to the adjacent edges of the ratchet bars and brace bars with the yoke of 15 the U member in alignment with the said space, and an adjusting bail swinging from said side bars and carrying outwardly projecting pins permitting their travelling through the space between the supporting 20 braces and ratchet bars and detachably entering the notches of the latter, the said supporting braces being pivoted to the side bars intermediate the bail and the lower ends of 25 said bars.

3. In witness whereof I have hereunto set my hand this 31st day of October, 1928.

OTTO H. KIESELER.
